(72) Inventor: **Joseph V. Ierulli**, Sarasota, FL (US)

FOREIGN PATENT DOCUMENTS

(73) Assignee: **Horizon IP Tech, LLC**, Honolulu, HI (US)

EP 855175 A1 7/1998
ES 289561 U 4/1986

(**) Term: **15 Years**

Primary Examiner — Bridget L Eland

(21) Appl. No.: **29/820,136**

(74) Attorney, Agent, or Firm — Christopher M. Ramsey; GrayRobinson, P.A.

(22) Filed: **Dec. 20, 2021**

CLAIM

The ornamental design for an external nasal dilator, as shown and described.

DESCRIPTION

(60) Continuation of application No. 29/731,654, filed on Apr. 16, 2020, now Pat. No. Des. 939,700, which is a division of application No. 29/667,495, filed on Oct. 22, 2018, now Pat. No. Des. 884,167.

FIG. 1 is a top plan view of a first embodiment of an external nasal dilator;

(51) **LOC (14) Cl.** **24-02**
(52) **U.S. Cl.**

FIG. 2 is a perspective view thereof, shown in a state of use;

(58) **Field of Classification Search**
USPC D24/135, 133, 189
CPC A61F 5/08; B29L 2031/753

FIG. 3 is a three-quarter perspective view thereof;

See application file for complete search history.

FIG. 4 is a top plan view of a second embodiment of an external nasal dilator;

(56) **References Cited**

FIG. 5 is a perspective view thereof, shown in a state of use;

U.S. PATENT DOCUMENTS

FIG. 6 is a three-quarter perspective view thereof;

5,383,891 A 1/1995 Walker
5,476,091 A 12/1995 Johnson
5,479,944 A 1/1996 Petruson
5,533,499 A 7/1996 Johnson
5,533,503 A 7/1996 Doubek et al.
5,546,929 A 8/1996 Muchin
5,549,103 A 8/1996 Johnson
RE35,408 E 12/1996 Petruson

FIG. 7 is a top plan view of a third embodiment of an external nasal dilator;

FIG. 8 is a perspective view thereof, shown in a state of use;

FIG. 9 is a three-quarter perspective view thereof;

FIG. 10 is a top plan view of a fourth embodiment of an external nasal dilator;

FIG. 11 is a perspective view thereof, shown in a state of use; and,

FIG. 12 is a three-quarter perspective view thereof.

The broken line showing of human facial features is directed to environment. The broken lines form no part of the claimed design in the embodiments in which they are shown.
